CLAIM

We claim the ornamental design for a writing instrument, as shown and described.

DESCRIPTION

FIG. 1 is an upper perspective view showing our new design for a writing instrument having a first writing tip.

FIG. 2 is a lower perspective view showing the design of FIG. 1.

FIG. 3 is a first side view showing the design of FIG. 1.

FIG. 4 is a second side view showing the design of FIG. 1.

FIG. 5 is a top view showing the design of FIG. 1.

FIG. 6 is a bottom view showing the design of FIG. 1.

FIG. 7 is an upper perspective view showing our new design for a writing instrument having a second writing tip.

FIG. 8 is a lower perspective view showing the design of FIG. 7.

FIG. 9 is a first side view showing the design of FIG. 7.

FIG. 10 is a second side view showing the design of FIG. 7.

FIG. 11 is a top view showing the design of FIG. 7.

FIG. 12 is a bottom view showing the design of FIG. 7.

FIG. 13 is a first upper perspective view showing the design of FIGS. 1 and 7, having a cap.

FIG. 14 is a second upper perspective view showing the design of FIGS. 1 and 7, having a cap; and,

FIG. 15 is an exploded perspective view showing the design of FIG. 1, having a cap.

The broken lines are included to show portions of the writing instrument that form no part of the claimed design.

1 Claim, 11 Drawing Sheets
